UNITED STATES PATENT OFFICE.

CHARLES N. FISHER, OF WILLIS, TEXAS, AND CHARLES L. DOWNES, OF JERSEY CITY, NEW JERSEY.

STYLOGRAPHIC FOUNTAIN-PEN.

SPECIFICATION forming part of Letters Patent No. 224,162, dated February 3, 1880.

Application filed September 12, 1879.

To all whom it may concern:

Be it known that we, CHARLES N. FISHER, of the town of Willis, Montgomery county, and State of Texas, (a native of Great Britain,) and 5 CHARLES L. DOWNES, of Jersey City, in the county of Hudson and State of New Jersey, have invented new and useful Improvements in Fountain-Pens; and we do hereby declare that the following is a full, clear, and exact 10 description of the construction and operation of the same, reference being had to the annexed drawings, making a part of this specification, and to the letters and figures of reference marked thereon.

15 Figure 1 of the drawings is an external view of our improved stylographic fountain-pen. Fig. 2 is a diametrical section through the pen, greatly enlarged. Figs. 3 and 4 are enlarged sectional details.

20 Similar letters of reference indicate corresponding parts.

This invention relates to stylographic fountain-pens wherein the ink is caused to flow from a reservoir in the handle of the pen, in 25 the act of writing, through a conical writing-point having a very fine tapered bore.

The nature of our invention consists in combining with a reservoir-handle having a tubular writing-point and a long clearing-needle 30 therefor an outer movable case or holder, a packing at the upper end thereof, a valve, and a spring, as will be hereinafter explained, whereby, in the act of writing, air will be admitted into the ink-reservoir and the ink 35 caused to flow freely from the point of the pen.

The invention also consists in adapting the case or holder, when it is detached from the valve-stem at the top of the reservoir-tube, to serve as a means for allowing a person to fill 40 the reservoir-tube with ink by pumping the same therein, as will be hereinafter explained.

In the annexed drawings, A designates the tube which forms the ink-reservoir, which tube may be made of hardened rubber or of any 45 other suitable material, and which may be made of one or two sections. To the lower end of this tube A a writing-point, C, is secured, which is tipped with the most durable metal or other substance that will answer the 50 purpose. The bore of this point is tapering

for the smaller end of a long needle-clearer to work in, for the purpose of keeping the bore open and free from the accumulation of sediment.

The upper end of the needle G is flexibly attached at e to a tubular stem, c, of a valve, b. This valve b has its seat against the lower end of a plug, F, which is secured into the upper end of the reservoir-tube A, and through which the prismatic portion c' passes freely. The 60 head or upper end of plug F is enlarged, so as to fit loosely inside of a tubular holder or case, B.

Between the head of the tubular plug F and a packing, g, a spring, s, is compressed and coiled around the valve-stem c. The packing g is confined on the screw-threaded portion of the valve-stem c, between two metal collars, m n, and this screw-threaded portion of valve-stem c passes through the top of the holder or case B, and receives a nut or screw-cap, E, on it, which firmly unites the stem of valve b to the top of holder B, but allows a longitudinal movement of this holder and the tube A on each other.

By grasping the holder B (the tube A being supplied with ink) and performing the movements of writing, a motion will be imparted to the tubes A and B which will cause the valve b to be frequently opened and shut and 80 air to be admitted in sufficient quantities into the reservoir-tube A to maintain a free supply of ink from the writing-point. The spring s closes the valve b when pressure is removed from the holder B.

Air is admitted between parts A and B to the space above the part A, and when part B is pressed down the valve b is opened to allow air to flow into the part A above the ink therein. When the pressure is removed from part 90 B the spring s will close the valve b. Thus it will be seen that during the act of writing the upper end of the part A is open to admit air into it.

To fill the reservoir-tube A, the nut E is removed from the valve-stem c, the point C is introduced into a vessel of ink, and the holder B moved up and down quickly. At each upward stroke of the holder B the finger should be pressed over the hole through its upper 100

end, and during each downward stroke given to the holder the finger should be removed from said hole. In this way ink can be pumped into the reservoir.

5 After supplying the reservoir with ink, and before commencing to write with the pen, the nut E should be screwed tightly on the valve-stem c, as shown in Fig. 2.

The extension a on the nut E is intended to receive the point-cap a' when this cap is removed from the point C.

Although we have shown and described a construction in which the air to be admitted to the ink-reservoir is conveyed through a passage between the two walls of the handle, yet we do not lay claim to this feature, as we are aware that pen-handles having double walls with air-passages between them have been used by others before our invention.

20 What we claim as new and as our invention is—

1. The reservoir-tube A, provided with plug F, valve b, valve-stem c, spring s, and packing g, in combination with the holder or case B and nut E, substantially as and for the purposes described. 25

2. The tube A, provided with the plug F, in combination with the valve b, provided with stem c, spring s, and packing g, and the holder B, provided with an opening through its upper end, substantially as and for the purposes described. 30

In testimony that we claim the above we have hereunto subscribed our names in the presence of two witnesses.

CHARLES NICHOLAS FISHER.
CHARLES L. DOWNES.
